United States Patent Office

Des. 183,367
Patented Aug. 12, 1958

183,367

SELF-PROPELLED CRANE

Glenn S. Park, Streator, Ill., assignor to Anthony Company, Streator, Ill., a corporation of Illinois

Application October 4, 1957, Serial No. 47,972

Term of patent 14 years

(Cl. D14—3)

Fig. 1

Des. 183,367

PAGE 2

Fig. 2

Des. 183,367

PAGE 3

Figure 1 is a front elevation for a self-propelled crane embodying my new design;

Figure 2 is a side elevation;

Figure 3 is a perspective view; and

Figure 4 is a side elevation showing the side of the device opposite that of Figure 2.

I claim:

The ornamental design for a self-propelled crane, as shown.
